The ornamental design for a personal mobility vehicle, as shown and described.

DESCRIPTION

FIG. 1 is a front, top, and left side perspective view of a personal mobility vehicle of our design;

FIG. 2 is a front, top, and right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The features illustrated in broken lines represent portions of the personal mobility vehicle that form no part of the claimed design.
